Primary Examiner — Kelley Donnelly

(74) *Attorney, Agent, or Firm* — Patent Law Works LLP

(57) **CLAIM**

The ornamental design for a bin, as shown.

DESCRIPTION

FIG. 1 is a perspective view of a first embodiment of a bin showing our new design;

FIG. 2 is a front view thereof;

FIG. 3 is a back view thereof;

FIG. 4 is a right side view thereof; the left side view being a mirror image;

FIG. 5 is a top view thereof;

FIG. 6 is a bottom view thereof;

FIG. 7 is a section view thereof taken through the line indicated in FIG. 2;

FIG. 8 is a perspective view of a second embodiment of a bin showing our new design;

FIG. 9 is a front view thereof;

FIG. 10 is a back view thereof;

FIG. 11 is a right side view thereof; the left side view being a mirror image;

FIG. 12 is a top view thereof;

FIG. 13 is a bottom view thereof; and,

FIG. 14 is a section view thereof taken through the line indicated in FIG. 9.

1 Claim, 7 Drawing Sheets
